Richard B. Duerst
ATTORNEY.

UNITED STATES PATENT OFFICE.

WILLIAM B. DUERST, OF PINE LAWN, MISSOURI, ASSIGNOR OF ONE-HALF TO FELIX WODICKA, OF ST. LOUIS, MISSOURI.

DIRIGIBLE HEADLIGHT.

1,375,138.

Specification of Letters Patent. Patented Apr. 19, 1921.

Application filed August 25, 1920. Serial No. 405,800.

To all whom it may concern:

Be it known that I, WILLIAM B. DUERST, a citizen of the United States, residing at Pine Lawn, in the county of St. Louis and 5 State of Missouri, have invented certain new and useful Improvements in Dirigible Headlights, of which the following is a specification.

This invention relates to dirigible head- 10 lights and has for its primary object to provide a device of this nature for motor vehicles which automatically adjusts itself so as to always throw its rays of light directly in the path of travel of the vehicle.

15 Another object of the invention is to generally improve upon dirigible headlights of this character by providing a device which will be of extremely simple, durable and inexpensive construction, one which is efficient 20 and reliable in operation and well adapted to the purpose for which it is designed.

With these and numerous other objects in view, the invention resides in certain novel features of construction and the combination, 25 and arrangement of parts as will be hereinafter fully described and claimed.

In the drawing:—

Figure 1 is a perspective view of the invention showing the necessary details of the 30 motor vehicle to which the invention is attached, and

Fig. 2 is a vertical section taken through a portion of the device showing various details thereof.

35 Referring to the accompanying drawing in detail it will be seen that 1 designates the chassis of the vehicle which is provided with the journal brackets 2 for receiving the crank arms 3 having the forked portions 4 upon their upper ends upon which are 40 mounted the dirigible headlights which are not shown in the drawings. An adjustable rod 5 formed in two sections and connected by means of bolts which pass through slots 45 so that the sections may be adjusted in relation to each other is situated immediately below the arms 6 of the cranks 3 and are attached thereto by means of the apertured knuckles 7 which are swivelly mounted on 50 the rod 5. One of these knuckles 7 is provided with a bolt that passes through one portion of the bracket 8 as shown in Fig. 2. This bracket 8 is of an angular construction provided with an elongated slot 9 in its vertical portion for receiving the bolt 10 which

is attached to the bar 11. This bar 11 is twisted so that one portion thereof will be at right angles to the other portion and at its lower end is bent so as to form the sleeve 12 which will surround the steering arm 13 of the 60 steering knuckle 14 which is mounted in the usual manner upon the front axletree 5.

Thus it will be seen that any rotary motion of the steering knuckle 14 will impart a swinging motion to the steering arm 13 65 which in turn will be transferred to the crank arms 3 through the bracket 8 and adjustable rod 5 in a manner which will be self-evident upon an inspection of the drawing. It will also be noted that collars 15 70 are provided upon the vertical portion of the cranks 3 and fixedly held in place by means of set screws 16 so that the crank portions 3 may be adjusted as may be desired and as may be found necessary upon different vehicles. It will also be noted that the slot 9 will allow the bar 11 to have a vertical play in relation to the bracket 8 as is absolutely necessary since the axletree 15 is always mounted to the chassis 1 by means of 80 a spring or other resilient devices. Thus it will be seen that the continual jarring of the axletree 15 when the vehicle is in motion will not be imparted to the other mechanisms of 85 the dirigible headlight.

From the foregoing description, taken in connection with the accompanying drawings, the construction and operation of the device will be readily understood without a more extended explanation. As numerous 90 changes in form, proportion, and in the minor details of construction may be resorted to without departing from the spirit of this invention, I do not wish to be limited to the construction herein shown and described other than as claimed. 95

Having thus described my invention what I claim as new is:—

1. In combination, a pair of headlight supporting cranks, an adjustable rod connecting the lower arms of said cranks, an angular bracket depending from said adjustable rod and provided with an elongated slot, a rod twisted so that one portion thereof will be at right angles to the other portion thereof, means attached to one end of the twisted bar so as to slidably engage the slot provided in the bracket, and a sleeve at its other end for engaging a steering arm of a motor vehicle. 100 105 110

2. In combination, rotatable means for supporting headlights, an angular bracket having one portion thereof provided with an elongated vertical slot, means for attaching 5 the other portion of the bracket to the rotatable means, a twisted bar, means at one end of the twisted bar adapted to slide in the slot of said bracket and a sleeve at its other

end for engaging a steering arm of a motor vehicle.

In testimony whereof I affix my signature in presence of two witnesses.

WILLIAM B. DUERST.
